US0D1059606S

(12) **United States Design Patent** (10) **Patent No.:** **US D1,059,606 S**
(45) **Date of Patent:** **** Jan. 28, 2025**

(54) **WEARABLE ROBOT**

(71) Applicant: **Samsung Electronics Co., Ltd.**, Suwon-si (KR)

(72) Inventors: **Jong-Deuk Son**, Suwon-si (KR); **Ji-yun Park**, Suwon-si (KR); **Jeonghan Song**, Suwon-si (KR)

(73) Assignee: **SAMSUNG ELECTRONICS CO., LTD.**, Suwon-si (KR)

(**) Term: **15 Years**

(21) Appl. No.: **29/889,781**

(22) Filed: **Apr. 17, 2023**

(30) **Foreign Application Priority Data**

Oct. 20, 2022 (KR) 30-2022-0042880

(57) **CLAIM**

The ornamental design for a wearable robot, as shown and described.

DESCRIPTION

FIG. 1 is a front perspective view of a wearable robot showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a rear perspective view thereof.

The dashed broken lines in the figures illustrate portions of the wearable robot that form no part of the claimed design. The dot-dash broken lines in the figures define boundaries of the claimed design and form no part of claimed design.

1 Claim, 8 Drawing Sheets
